DESIGN FOR A DRAPED PARTITION

Morris Lange, Cleveland Heights, Ohio

Application January 11, 1937, Serial No. 67,000

Term of patent 7 years

To all whom it may concern:

Be it known that I, Morris Lange, a citizen of the United States, residing at Cleveland Heights, in the county of Cuyahoga and State of Ohio, have invented a new, original, and ornamental Design for Draped Partitions, of which the following is a specification, reference being had to the accompanying drawing, forming part thereof.

I claim:

The ornamental design for a draped partition, as shown.

MORRIS LANGE.
